CASKET DISPLAY CANOPY

Clara W. Arnold, East Cleveland, and Oscar J. Hinger, Cleveland, Ohio, assignors to The Ohio Blanket Company, East Cleveland, Ohio, a corporation of Ohio

Application December 3, 1940, Serial No. 368,350

12 Claims. (Cl. 135—5)

This invention relates to curtain or drapery display backgrounds, and more specifically, to a casket display canopy, adapted to form a dignified background or setting for burial caskets, and the like.

An object of this invention is to provide a readily adjustable drapery display supporting means which can be conveniently taken apart and packed for transportation.

Another object is to provide means for evenly lighting a body disposed in a casket, thereby eliminating the necessity of applying cosmetics to the body, in order to give it a semblance of its natural appearance.

Another object is to provide a casket display canopy which creates an impression of depth and provides ample display near the casket space for flowers, emblems, and the like.

Other objects are, to provide a casket display means which are dignified and attractive in appearance, and may be adjusted as to color schemes and disposition of the relative position of the various drapes, in accordance with the requirements of each individual case.

Other and further objects will appear during the course of the following description.

In the drawings accompanying this application and forming a part of this specification:

Figure 1 is a perspective view of a casket display canopy embodying our invention with parts broken away, the view being taken from the point in front of and considerably above the top of the canopy, looking diagonally downward on the canopy.

Figure 2 is an enlarged broken perspective view of a part of the drapery supporting means.

Figure 3 is a broken sectional view taken on the line 3—3 of Figure 2.

Figure 4 is a broken elevational view of the side of the drapery supporting means drawn to a smaller scale.

Figure 5 is an enlarged sectional view taken on the line 5—5 of Figure 1 showing the lighting means.

Figure 6 is a broken sectional view taken on the line 6—6 of Figure 1.

Figure 7 is a broken perspective view of a modified form of drapery supporting means.

Figure 8 is a broken elevational view of parts shown in Figure 7 and taken at an angle thereto.

Figure 9 is a broken perspective view of another modified form of drapery supporting means, while

Figure 10 is a broken elevational view of parts shown in Figure 9, and taken at an angle thereto.

In the drawings the preferred form of our invention, illustrated in Figures 1 through 6, the numeral 11 refers generally to our casket display canopy comprising a framework 12 having side and back drapes 13 mounted thereon. The drapes 13 may be draped over the framework 12 in such manner that inner and outer folds are provided, thereby permitting interchangeability between the inner and outer drapery folds, for permitting choice of colors and selective choice of drapes to suit individual choice. Obviously, drapes of various materials, colors, and sizes may be used, although we have found that plain drapes, without designs, form the most satisfactory setting for a casket.

The framework 12, as shown in Figure 1, includes a pair of standards 14 mounted on feet 15, pivotally mounted on a support rod 16 and connected thereto by link members 17, supporting the feet 15 when the standards 14 are in use, and permitting the same to be collapsed and stored away when not in use, in an obvious manner.

The upper end of the support rod 16 telescopically receives a second support rod 18 and is releasably locked thereto by means of set screw 19, while a third support rod 20 telescopically received within the upper end of the support rod 18 is releasably locked thereto by means of a set screw 21. The construction and arrangement of the parts forming the standards 14, it will be seen, is such that they may be readily adjusted to various lengths and thus possess a wide range of utility.

Support rods 20 are provided with reduced portions receiving sleeves 22 mounted thereon in such manner that the sleeves 22 may be rotated thereon, while arms 23 fixedly connected in the sleeves 22 extend horizontally therefrom, as shown in Figures 1, 2, 3, and 4. The outer ends of the arms 23 are provided with a pivotal mounting 24 securing an outer curved arm 25 thereto in such manner that it may be swung on a vertical pivot. The curved arm 25 permits the hanging of drapes thereon in such manner that in appearance it creates somewhat the effect of a pillar, and the position of the same may be varied to suit individual requirements.

The upper end of each sleeve 22 is adapted telescopically to receive a reduced end of a rod 20a, each rod 20a having a curved recess in the top thereof, these recesses serving conveniently to receive and support the ends of rods 26, 27 respectively, which may be suitably welded or otherwise fastened in the respective recesses. Each rod 26, 27 is here shown (in Figure 1) as

extending at right angles to the axis of the respective rod 20a by which it is supported, the rods being here shown as extending toward each other at a rearward angle away from the plane defined by the vertical standards 14. The rods 26, 27 may be joined by any suitable joint means 28. It will be evident that in the embodiment shown the rods 26, 27 define a plane at right angles to the plane defined by the standards 14. By having the rods 26, 27 extend rearwardly, drapes hanging vertically downwardly therefrom form rear wall means which in this instance comprises two components defining a rearwardly extending dihedral recess, giving desirable depth of the drapery rearwardly of the casket and permitting the placement in the recess of flowers, emblems, and the like. However, while this construction is desirable it is not essential since the rear wall means may be plane or of other form. The drapes hanging from the arms 23 are adapted to form a pair of side wall means of the canopy which side wall means may extend from their respective junctions with the sides of the rear wall means at any desired angle.

Collars 29 mounted around the tops of the rods 20a are provided with parallel rearwardly extending portions 30, while set screws 31 serve to releasably lock said collar 29 on the rod 20 in an obvious manner. A pair of cooperating upwardly extending arms 32 secured to the portions 30 of the collars 29, are connected at the bottom by a pin 33 and at the top by a pin 34, adapted to be disposed in a curved recess 35 of an arm 36, forming one top side of the framework 12, while the rear of the arm 36 is adapted to rest on the rear rod 26. A pin 40 extending through the side arm 36 serves to retain it in locked position as shown in Figures 2 and 3.

It will be apparent that the angle, with respect to a generally horizontal plane, which each rod 26, 27 makes with the respective arm 36 will depend on the rotative position in which the collars 29 are locked or fixed to the respective rods 20a. In Figure 2 the rod 26 is shown as substantially at right angles to the arm 36 but preferably, as shown in Figure 1, each rod 26, 27 extends rearwardly of the plane defined by the standards 14 and so each makes an angle greater than 90° with the respective forwardly extending arm 36.

The forward end of the arm 36 is curved around towards the opposite framework side forming a front portion 37, having a front arm 38 secured thereto by means of a thumb screw 39. If desired, the front arm 38 may be made of more than one member and formed in any suitable manner. The front arm 38 is connected at its other end, at the other side of the framework, to a side arm similar to the side arm 36. This arrangement of the parts permits the ready assembling and taking apart of the framework 12. For example, the curved side arms 36 may be removed from the framework 12 by merely raising the front arm 38 until the curved portion 35 of the arm 36 is lowered so that it is not engaged by the pin 34, thus permitting the arms 36 connected by the arm 38, to be readily lifted out, in an obvious manner.

A source of light is provided, in the form of an elongated fluorescent lamp 41, suitably mounted in a reflector 42 including a top 43, rear 44, and short front wall 45. The reflector 42 may be formed of suitable material such as metal or the like, which if desired, may be coated on its inner surfaces with reflector materials of suitable char-

acter, and is mounted on the inner surface of the front arm 38 in any suitable manner. By using an elongated light source of uniform brilliance and placing it in a reflector, as described, we have discovered that a soft uniform light is provided for a body located in a casket placed in the canopy 11, and due to such even illumination the body has an appearance of naturalness and is free from shadows, which without such illumination could not be accomplished.

Fabric forming the top wall or ceiling of the canopy is desirably provided and this fabric extends over and is supported by the frame comprising the arms 26, 27 and the side arms 36 and the front arm 38, and is desirably extended sideways from each of the arms 36 so as to hang loosely over the arms 23 in the form of gusset-like portions. One of these sidewardly extending gusset-like portions is visible at the top of the right of Figure 1. The fabric forming the top wall of the canopy desirably is extended so as to hang downwardly over the front arm 38 in the form of a short drape 46 and is suitably fastened to the front arm at spaced places 47, as by means of snap fasteners. The short drape 46 conceals the lamp 41 when the canopy is viewed from the outside of its general confines.

It will be evident that by adjusting the collars 29 up or down, thereby adjusting the pin 34, the outer ends of the side arms 36 may be caused to move down or up respectively, so that the top or ceiling of the canopy may be adjusted so as to be horizontal or to slant forward either downwardly or upwardly, but desirably the top slants upwardly.

A slightly modified form of our invention shown in Figures 7 and 8, relates to changes made in the manner of mounting the rear rods and side arms on the standards 14. In this form of our invention the rear end of the side arm 36a, instead of resting on the rear rod 26a, is secured to a sleeve 48 rotatably mounted on the support rod 20, thus permitting the arm 36a to swing to various positions for placing the inner side margins of the canopy at various desired angular relations to the back thereof. The rear rod 26a is similarly secured to a sleeve 49 rotatably mounted on the support rod 20, thus permitting changes in the angular relation of the rod 26a on the standard 14.

Another modified form, shown in Figures 9 and 10, provides for a corresponding mounting of the rod 26 on the standard 14 and adds changes to the manner of mounting the support rod 36b. In this form of the invention a collar 50, surrounding the support rod 20, is secured to the rod 36b by means of a pin 51, while a thumb screw 52 provides for releasably mounting the collar 50 on the rod 20. A lower collar 53 corresponding to the collar 50 is releasably mounted on the rod 20 by means of thumb screw 54, while an upper link 55, secured to the arm 36b by a pin 56, operates with a corresponding lower link secured thereto by a pin 58, and a pin 59 secures the link 57 to the lower collar 53.

The foregoing construction permits the collars 50 and 53 to be readily adjusted to alter the perpendicular height of the arm 36b at varying distances from the floor, and also permits the folding of the arm 36b along the side of the perpendicular support rods, this feature presenting the distinct advantage of facilitating the storing of the device in a case, the desirability of such being apparent when it is considered that

the same device is used by undertakers at successive funerals.

The side and back drapes 13 may be made of suitable material, and if desired, may be hung double over the framework 12, so that a different color scheme may be provided on each side, thus giving a selection of color schemes to harmonize with the surroundings. The height of the standards 14 may be varied in an obvious manner for forming a canopy of desired proportion. The angular position of the arms 23 may be varied to suit individual requirements. Likewise, the position of the curved arm 25 may be varied in an obvious manner. The angular relation of the sides and front portions of the framework 12, as shown in Figures 1, 2, 3, and 4 may be varied by raising or lowering the collar 29, and such parts may be disassembled in an obvious manner.

The position and arrangement of the elongated light 41 provides uniform lighting means, which throws evenly diffused light along a body placed in a casket disposed in the canopy, while the front drape 46 conceals the light source. Thus, the canopy 11, by providing its own lighting means, may be placed at any desired point in a room away from a window or any outside source of light.

The canopy disclosed herein is not limited to displaying caskets, as it is equally adapted to be used in various types of merchandise displays and the like. By changing the height of the standards and the angular relations of the various parts of the standards, a canopy of various sizes and proportions may be formed to suit individual requirements. The device may be readily assembled and disassembled to permit storage in cases to facilitate handling and transportation.

It will be apparent to those skilled in the art, that the invention disclosed herein may be variously changed, used, or modified, without departing from the spirit of the invention or sacrificing the advantages thereof, and that the embodiment herein disclosed is illustrative only, and that our invention is not limited thereto.

We claim:

1. Means for supporting drapes, comprising: means including an arm for supporting a drape; and means for supporting said arm in a desired position, said arm-supporting means including a fulcrum element engageable downwardly by an under outer surface of an intermediate portion of said arm, and including a stop element engageable upwardly by an upper outer surface of a portion of said arm spaced from said fulcrum element.

2. Means for supporting drapes, comprising: means including an arm for supporting a drape; means for supporting said arm in a desired position, said arm-supporting means including a fulcrum element engageable downwardly by an under outer surface of an intermediate portion of said arm, and including a stop element engageable upwardly by an upper outer surface of a portion of said arm spaced from said fulcrum element; and one of said surfaces and the respective element engageable thereby being relatively so constructed and arranged that said arm and said arm-supporting means are relatively interlocked when said surfaces are in engagement with said elements and so that said arm may be released and removed from said supporting means merely by predetermined relative rotative and translatory movement of said arm and said supporting means.

3. Means for supporting drapes, comprising: means including an arm for supporting a drape; and means for supporting said arm in a desired position, said arm-supporting means including a fulcrum element engageable downwardly by an under outer surface of an intermediate portion of said arm, and including a stop element engageable upwardly by an upper outer surface of said fulcrum element, one of said elements being a pin extending transversely of said arm, and the surface of said arm engageable with said pin being provided by a transverse recess on said arm.

4. Means for supporting drapes, comprising: means including an arm for supporting a drape; and means for supporting said arm in a desired position, said arm-supporting means, including a fulcrum element engageable downwardly by an under outer surface of an intermediate portion of said arm, and including a stop element comprising a pin extending transversely of said arm and engageable upwardly by a transverse recess in an upper outer surface of said arm and spaced from said fulcrum.

5. Means for supporting drapes, comprising: a standard comprising a vertical member and a sleeve telescopically assemblable with said member and rotatable about the axis of said member; means including a first arm for supporting a drape and carried by and extending laterally from said sleeve; said standard further comprising support means having a portion telescopically assemblable with and rotatable in said sleeve; means including a second arm for supporting a drape; said support means including a fulcrum element engageable downwardly by an under outer surface of an intermediate portion of said second arm, and including a stop element engageable upwardly by an upper outer surface of a portion of said second arm spaced from said fulcrum element.

6. Means for supporting drapes, comprising: a standard comprising a vertical member and a sleeve telescopically assemblable with said member and rotatable about the axis of said member; means including a first arm for supporting a drape carried by and extending laterally from said sleeve; said standard further comprising support means having a portion telescopically assemblable with and rotatable in said sleeve; means including a second arm for supporting a drape; said support means comprising means including a third arm for supporting a drape, said third arm extending laterally from the axis of said portion and serving as a fulcrum element engageable downwardly by an under outer surface of an intermediate portion of said second arm, and said support means including stop means engageable upwardly by an upper outer surface of a portion of said second arm spaced from said fulcrum element.

7. A canopy for displaying an object, comprising: rear wall means adapted to be positioned generally vertically at the rear of the object; top wall means adapted to be positioned generally horizontally a desired distance from a floor and to extend forwardly from said rear wall means over the object; support means comprising standards for engaging the floor at spaced places, and comprising frame means supported by said standards in a generally horizontal position and constructed and arranged for engaging said top wall means from underneath and supporting said top wall means in said generally horizontal position and for suspending said rear wall means in said

generally vertical position from the rear of said frame means; and means for supporting from said frame means underneath and adjacent said top wall means a source of light for illuminating the object.

8. A canopy for displaying an object, comprising: rear wall means adapted to be positioned generally vertically at the rear of the object; top wall means adapted to be positioned generally horizontally a desired distance from a floor and to extend forwardly from said rear wall means over the object; support means comprising standards for engaging the floor at spaced places, and comprising frame means supported by said standards in a generally horizontal position and constructed and arranged for engaging said top wall means from underneath and supporting said top wall means in said generally horizontal position and for suspending said rear wall means in said generally vertical position from the rear of said frame means; and means for supporting from the front of said frame means underneath and adjacent said top wall means a source of light for illuminating the object from above and in front thereof.

9. A canopy for displaying an object, comprising: rear wall means adapted to be positioned generally vertically at the rear of the object; top wall means adapted to be positioned generally horizontally a desired distance from a floor and to extend forwardly from said rear wall means over the object; support means comprising standards for engaging the floor at spaced places, and comprising frame means supported by said standards in a generally horizontal position, said frame means including rear arm means extending between and supported by said standards and horizontally spaced side arm means extending generally horizontally forward from said rear arm means, and front arm means interconnecting said side arm means at their front ends, said frame means being constructed and arranged for engaging said top wall means from underneath and supporting said top wall means in said generally horizontal position and for suspending said rear wall means in said generally vertical position from said rear arm means; and means for supporting from said front arm means a source of light for illuminating the object from above and from in front thereof.

10. A canopy for displaying an object, comprising: rear wall means adapted to be positioned generally vertically at the rear of the object; a pair of side wall means adapted to be positioned generally vertically at opposite sides of said rear wall means; top wall means adapted to be positioned generally horizontally a desired distance from a floor and to extend forwardly from said rear wall means over the object; support means comprising standards, approximately at the respective junctions of said side wall means and rear wall means, for engaging the floor at approximately the intersections of said junctions with the floor, and comprising frame means supported by said standards in a generally horizontal position, and constructed and arranged for engaging said top wall means from underneath and supporting said top wall means in said generally horizontal position and for suspending said

rear wall means in said generally vertical position from the rear of said frame means; and said support means including a pair of arms for supporting said side wall means respectively said arms being swingably mounted on said standards respectively and extending laterally from said standards to enable said side wall means to be supported in selected angular relation to said rear wall means.

11. A canopy for displaying an object, comprising: rear wall means adapted to be positioned generally vertically at the rear of the object; a pair of side wall means adapted to be positioned generally vertically at opposite sides of said rear wall means; top wall means adapted to be positioned generally horizontally a desired distance from a floor and to extend forwardly from said rear wall means over the object; support means comprising standards, approximately at the respective junctions of said side wall means and rear wall means, for engaging the floor at approximately the intersections of said junctions with the floor, and comprising frame means supported by said standards in a generally horizontal position and constructed and arranged for engaging said top wall means from underneath and supporting said top wall means in said generally horizontal position and for suspending said rear wall means in said generally vertical position from the rear of said frame means; said support means including a pair of arms for supporting said side wall means respectively said arms being swingably mounted on said standards respectively and extending laterally from said standards to enable said side wall means to be supported in selected angular relation to said rear wall means; and gusset-like top wall portions extending laterally from the respective lateral margins of said top wall means to the tops of said side wall means respectively.

12. A canopy for displaying an object, comprising: rear wall means adapted to be positioned generally vertically at the rear of the object; top wall means adapted to be positioned generally horizontally a desired distance from a floor and to extend forwardly from said rear wall means over the object; support means comprising standards for engaging the floor at spaced places, and comprising frame means supported by said standards in a generally horizontal position, said frame means including rear arm means comprising portions supported by said standards and extending therefrom respectively generally horizontally toward each other rearwardly at an angle, and further including horizontally spaced side arm means extending generally parallel horizontally forward from said standards, and further including front arm means interconnecting said side arm means at their front ends, said frame means being constructed and arranged for engaging said top wall means from underneath and supporting said top wall means in said generally horizontal position and for suspending said rear wall means in said generally vertical position from said rear arm means in the form of a dihedral angle.
